UNITED STATES PATENT OFFICE.

PHILIP FREEMAN KITTOE, OF GALENA, ILLINOIS.

CIRCUIT-BREAKER.

1,380,216.

Specification of Letters Patent. Patented May 31, 1921.

Application filed August 3, 1920. Serial No. 400,968.

To all whom it may concern:

Be it known that I, PHILIP F. KITTOE, residing at Galena, in the county of Jo Daviess and State of Illinois, have invented new and useful Improvements in Circuit-
5 Breakers, of which the following is a specification.

This invention relates to improvements in circuit breakers and especially to pressure operated circuit breakers designed primarily
10 for use in connection with dental vulcanizers.

An object of the present invention is the provision of a circuit breaker which will operate to open a circuit at a predetermined
15 pressure, means being provided to adjust the device to regulate the degree of pressure at which it will operate.

Another object of the invention is the provision of a circuit breaker which is simple
20 in construction and positive in operation and which may be used in connection with either air or liquid operated mechanisms.

With the above and other objects in view, the invention further includes the following
25 novel features and details of construction, to be hereinafter more fully described, illustrated in the accompanying drawings and pointed out in the appended claims.

In the drawings:—

30 Figure 1 is an elevation of a circuit breaker embodying the present invention.

Fig. 2 is a central longitudinal sectional view of the same.

Fig. 3 is a transverse section.

35 Referring in detail to the drawings, wherein like characters of reference denote corresponding parts, the circuit breaker is shown as comprising a cylinder 10 which is closed at one end by means of a removable
40 cap 11 and is provided at its other end with a nipple 12 having an opening 13 therefor by means of which the cylinder may be connected to a suitable source of pressure.

45 Operating within the cylinder 10 is a piston 14 which is equipped with a packing ring 15 and is provided with a rod 16 which extends through an opening in the cap 11, the rod being bent upon itself as shown at 17 so as to provide an arm which forms a
50 removable contact member 18. The contact member 18 is insulated from the rod 16 proper as shown at 19, while the extremity

of the said arm is formed of fiber or other insulating material as shown at 20.

Mounted upon the cylinder 10 is a ring
55 21 which may be adjusted at any point within the length of the cylinder by means of a set screw 22. The ring 21 is provided with a hollow arm 23 and a transverse opening 24, the latter forming a guide for the
60 movable contact member 18. Located within the hollow arm 23 is a contact point 25 which engages the movable contact member 18 and is yieldingly held in such engagement by means of a coiled spring 26. The
65 outer end of the arm 23 is provided with a binding screw 27 for connection with one of the lead wires of an electric circuit.

The movable contact member 18 is connected in the circuit by any preferred means,
70 the means shown consisting of a collar 28 which is adjusted upon the contact member 18 by means of a screw 29 which also provides a binding post for connection with the
75 circuit wire.

Located within the cylinder 10 and surrounding the rod 16 is a coiled spring 30 which acts to normally force the piston toward one end of the cylinder, in which position the contact point 25 is in engagement with the contact member 18 to complete the circuit. Pressure entering through the passage 13 will move the piston 14 against the ends of the spring and cause the contact point 25 to engage the insulated end 20 of
80 the contact member 18 and interrupt the circuit. The point at which this interruption will occur may be regulated by the position of the ring 21 so that the amount of pressure necessary to interrupt the circuit may
85 be increased or decreased as desired.

The invention is susceptible of various changes in its form, proportions and minor details of construction and the right is herein reserved to make such changes as properly fall within the scope of the appended claims.

Having described the invention, what is claimed is:—

1. A circuit breaker comprising a cylinder, a spring actuated piston therein, an adjustable contact member carried by the cylinder, a movable contact member carried by the piston and normally contacting with the adjustable contact member, said movable

100

105

contact member including spaced parallel arms connected at one end and means whereby pressure may be applied to the piston to move the latter against the action of the spring to separate the contact members.

2. A circuit breaker comprising a cylinder, a spring actuated piston therein, an adjustable contact member carried by the cylinder, a movable contact member carried by

the piston and normally contacting with the 13 adjustable contact member, said movable contact member comprising a substantially U shaped rod and means whereby pressure may be applied to the piston to move the latter against the action of the spring to 15 separate the contact members.

In testimony whereof I affix my signature.
PHILIP FREEMAN KITTOE.
